UNIVERSAL MOP

Filed March 19, 1928

Fig. 1.

Harry Hertzberg Inventor

By his Attorney

Martin Joachimsohn

UNITED STATES PATENT OFFICE

HARRY HERTZBERG, OF BROOKLYN, NEW YORK

UNIVERSAL MOP

Application filed March 19, 1928. Serial No. 262,778.

This invention relates to mops and dusters of the rotatable type in which the mop material is clamped by means of twisting a plurality of wires about each other.

5 It is the object of the present invention to provide a mop of this type with a plurality of dusters which may be rotated around a complete circle about their common axis and simultaneously be oscillated to describe a 10 large arc about a second axis.

It is another object of this invention to clamp said dusters in any position they may assume through the combined movements by a single clamping means.

15 It is a further object of the invention to provide a mop which has two dusting elements of which each may be used independently of the other or simultaneously with each other. With these and other objects in view 20 the invention consists in certain novel combinations and arrangements of parts herein- after more clearly described and finally pointed out in the appended claims and illustrated in the accompanying drawings in which:

25 Fig. 1 is a front elevation of my universal mop, parts of cap 40 and sleeve 30 are broken away to show the interior construction.

Fig. 2 is a sectional elevation on line 2—2 of Fig. 1.

30 The illustrations in the drawing show a double mop head consisting of a plurality of wire strands 10 which are twisted about each other and hold mop material 11 between them. The wires 10 are bare of mop material 35 in their middle part 10^a which is covered by an I shaped tubular sleeve 30. Those parts of wires 10 which protrude from either side of sleeve 30 have each the form of a complete ring 100 and 101. Each wire ring holds

40 mop cords as above described comprising a separate ring shaped duster or mop. The wires of both rings extend clockwise around the circle from their middle part 10^a towards their ends. In this manner they assume the 45 shape of an S. The extreme ends of wires 10 are preferably welded into the tubular sleeve 30 to form a rigid connection at these points and to avoid deformation of the ring shaped dusters closing the aforementioned S 50 so that the mops have the shape of a dumb-

bell. The sleeve 30 between these mop heads is journalled in two bearing- or clamping- plates which enclose the cylindrical part of sleeve 30, with their semicylindrical parts 40, while their flat portions 41 lie flat against 55 a plate 51 which forms a part of the tubular mop holder 50. The plates 41 are held on laminated plate 51 by means of screw 52 and wing nut 53 about the axis of which they may oscillate so that their journal por- 60 tions with sleeve 30 and rings 100 and 101 can be oscillated to assume extreme positions x or y indicated by dotted lines in Fig. 1 and any other position between these ex- tremes. The two clamping plates 41 permit 65 the rotation of the mop in their bearing por- tion 40 and the clamping of the mop in any position in which it may be placed. Plate 51 is integral with mop holder socket 54, both are made from a piece of commercial brass 70 or steel tubing which has threads 55 impressed thereon to hold a mop stick 56. The for- ward end of this piece of tubing is com- pressed so that the walls of the tube lie flat 75 against each other and form thereby the lami- nated plate 51 on which the clamping plates 41 are held by screw 52 and nut 53.

In operation this universal mop permits of many applications for which other mops cannot be used as each one of the two looped portions can be placed in front of the mop stick and used singly. Narrow spaces other- wise inaccessible can be cleaned in this manner, railings, the edges of boards and nar- row ledges can be cleaned simultaneously on 80 both sides by placing the two loops on op- posite sides thereof. Each mop can be used separate until dirty or worn and then the second mop may take its place. In any po- sition into which either mop or ring may be 85 placed it can be rotated completely in bearing 40 describing a sphere thereby which is of small diameter and particularly useful for cleaning corners formed by two walls and ceiling for instance.

90 While I have shown and described the pre- ferred form of my universal mop it is to be understood that such changes may be made in its arrangement and in the construction 95 of the minor details or form of the two mop 100

rings as come within the scope of the invention defined in the claims without departure from the spirit of the invention and the principle involved.

Having thus described my invention, what I claim as new and desire to secure by Letters Patent is:

1. A mop comprising a pair of mop rings consisting of wires twisted about each other and a journal portion joining said rings, mop material held between the twisted wires of said rings, a bearing mounting said journal portion and said rings for rotation, a holder adapted for attachment to a mop stick and a pivot arranged transversely to said journal portion joining said bearing to said holder.

2. A mop structure consisting of two loop shaped mops arranged in a common plane, said mops being joined to each other by a middle part spacing said mops from each other, a bearing mounting said middle part and said mops for rotation therein, a mop holder adapted for attachment to a mop stick and a pivot joining said journal oscillatably thereto, comprising means to align both mop loops with the mop stick axis.

3. A mop structure consisting of wires twisted about each other and forming two loops joined by a straight portion between said loops, mop material on said loops held by the twist of said wires, a sleeve surrounding said straight portion, a pair of bearing plates having channels for holding said sleeve rotatably between them, a holder adapted for attachment to a mop stick and a pivot joining said holder hingedly to said bearing plates and means on said pivot for clamping said bearing plates against said sleeve.

4. A mop structure consisting of wires twisted about each other and forming two separate loops joined by a straight portion between said loops, mop material on said loops held by the twist of said wires, a tubular sleeve surrounding said straight portion joining the free ends of said wires transversely to said straight portion for closing said loops and forming means for attaching said mop loops rotatably to a mop holder between said loops.

5. In a mop structure of the kind described, a mop holder having a tubular portion adapted for attachment to a mop stick, a plate portion on said holder, a pair of bearing plates lying against the sides of said plate portion, a transverse groove being formed in each journal plate forming together a cylindrical bearing box adapted to hold a mop frame for rotation and a pivot bolt joining said bearing plates oscillatably to said plate portion, and means on said bolt for clamping said bearing plates fixedly to said frame and said plate portion.

6. In a mop structure the combination with a looped mop frame holding mop material, of a straight middle part on said frame, a

bearing holding said middle part for rotation therein, a holder adapted for attachment to a mop handle and a pivot joining said holder to said bearing providing for oscillation of said frame about an axis perpendicular to said middle part.

7. In a mop structure in combination a frame supporting mop material, a holder providing means for attachment of said frame to a mop handle, said holder having a flat portion, a pair of clamping plates lying against the sides of said flat portion and having complementary grooves forming a journal bearing, a pivot bolt joining said plates to said flat portion, said mop frame being interposed between said clamping plates in said grooves and means on said pivot bolt for clamping said plates to said holder in a plurality of angular positions with the axis of the mop handle.

Signed at Brooklyn, in the county of Kings and State of New York this 12th day of March, A. D. 1928.

HARRY HERTZBERG.
